UNITED STATES PATENT OFFICE

SIEGMUND LOEWE, OF BERLIN, FRIEDENAU, GERMANY, ASSIGNOR TO RADIO CORPORATION OF AMERICA, A CORPORATION OF DELAWARE

AMPLIFIER

Application filed November 11, 1928, Serial No. 147,643, and in Germany November 12, 1925.

This invention relates to an amplifier, and more particularly to an amplifier using both hot and cold cathodes.

The problem of making electronic tubes with cold cathodes is, fundamentally speaking, feasible and solvable in various ways. For example, the use of radio-active substances, photo-electrically active surfaces, chemical combinations exhibiting slowly preceding reactions, metallic alloys of high emissivity, and the like, would afford workable schemes.

However, it has been found difficult to produce, by means of cold cathodes, electron currents of a strength sufficient for the sustained, strong operation of a telephone or loud-speaker. Such currents must be of an order of magnitude of several milliamperes; whereas, the largest currents that can be produced with cold cathodes are smaller; that is to say, of a magnitude insufficient to operate a loud speaker.

It is an object of this invention to provide an amplifier, in which one or more cold electron emitting sources may be used, for the operation of relatively large current-drawing devices.

If it is not possible to obtain the comparatively high electronic emissions required in the last stage of a receiving amplifier or any other arrangement of the present kind by the aid of cold cathodes, it will be found feasible to use such cathodes with resistance-coupling in the first stages, and with a hot cathode tube in the end stage. Broadly, the invention consists in utilizing a hot-cathode tube as the end stage, while using cold electron-emission sources in the preceding stages. The saving attainable by this arrangement in the line of heating current, and the structural simplification of the tubes and receiving equipment is considerable. This will be further explained below.

Another object of this invention is to cause, either directly or indirectly, the electron-emission of the cathodes of the first few stages by the phenomena occurring in the last stage. This may be explained as follows:

Since, in the first stages about one-hundredth of the emission is required which the

last power stage has to deliver for the operation of the telephone or the loud-speaker, it is sufficient to branch off a small fraction of the emission of the last heated cathode in order to run thereby the preceding amplifier stages. Especially in the case of what is known as multiple-unit systems where the first stages and the final stage are enclosed in the same vacuous space, it is possible to thus obtain more far-reaching results.

The emission in the preceding stages may be accomplished by using the luminous effect of the last hot tube. That is, by the utilization of photo-electric effects, the small requisite emission is obtained. This scheme is very practicable in the case of tube systems built and assembled in a common vacuous space, and it may also be applied to separately mounted tubes.

A very faint light such as that of dull oxide cathodes is sufficient to produce an appreciable photo-electric electron-emission. If daylight is available in the first stages, and if these stages are photo-electrically excited, this natural source of light will, in general, prove adequate. But when such tubes are encased, so that light is excluded, for the constant maintenance of photo-electric effects in the preceding stages, it is possible to take advantage of the luminous effect which the thermo-electrically operated last stage will produce and which heretofore has been of no use whatever.

It will be evident that by an analogous application of the basic idea, it is also possible to utilize the thermal radiation of the incandescent cathode for the thermo-electric release of the small volumes of electrons that are required in the preceding stages or systems.

My invention, which will be explained and described by the aid of a multiple-unit system built into an evacuated vessel, will illustrate an application of the preceding general ideas. In the drawing, Figure 1 represents an amplifier wherein the electron emission from a preceding stage is caused by light falling upon the cathode of that stage;

Figure 2 shows a modification wherein such an electron emission may be caused by

the emission of light and electrons from the cathode of an end stage.

Referring to Figure 1, 1 indicates a glass vessel in which two multiple electrode amplifier systems each comprising a cathode have been placed. The lower system represents the final stage, which, according to this invention, is to be worked theremo-electrically. 2 is the filament or cathode of this system, the 10 filament being, for instance, of the hairpin pattern. The grid or control electrode is indicated at 3, and the cylindrical anode or plate is denoted by 4. The upper system comprises a cold cathode which is indicated by a 15 cylinder 5 which may be connected single-pole fashion with the filament 2 by connector 21. The surface of this cylinder shall be assumed to be photo-electrically active. The cylinder may be coated with thallium, 20 sulfite, potassium hydride, selenium, rubidium or the like. It receives its photo-electric energy by means of the light or heat radiation issuing from filament 2. In this case the emission is effected by photo-electric 25 means. The re-supply of electrons is effected through the connecting lead 21 with the heated cathode. About the body 5 may be wrapped a control element 6, while the entire system is enveloped by a likewise cylindrical anode or plate 8. Of course, the anodes, or part thereof, may be made of wire 30 gauze or lattice or may otherwise be perforated or apertured in order that, if necessary, sufficient light may be admitted. The 35 interior of the glass wall 1 may be coated with a reflecting surface 1'. There will then be such a complete reflection of the light from all sides of the glass wall that the photo-electrically active surface 5 is always 40 sufficiently illuminated as long as the filament 2 is incandescent. Of course, if the filament 2 burns at dull incandescence photo-electric substances will preferably be chosen which are predominantly sensitive to long 45 wave luminous rays. If the filament burns brighter, photo-electric substances sensitive to the radiations of shorter wave-lengths should be chosen.

The systems can be used in any desired 50 manner. For example, the grid 6 may have a lead-in at 7. The plate 8 may be connected by way of a high-ohmic resistance 9 disposed inside the tube through a lead-in 10 with the plate battery or else directly with the plate 55 4 in which latter case the lead-in or seal can be dispensed with. The grid 3 is united through a stopper or block condenser 11 with the plate 8. The lead for plate 4 is brought out at 12 and carries the controlled power 60 current for the operation of the consuming or working device connected in the rear of the tube.

The arrangement hereinbefore described 65 can be used for radio frequency or low frequency amplification. The control currents

are fed in between lead 7 and the lead 13. They control the system 5, 6, 8 working with a cold cathode according to this invention, the ensuing alternating potentials being transferred by way of condenser 11 to the grid 3. By means of these control potentials the power tube 2, 3, 4, is controlled. It is evident that in lieu of the two systems here shown by way of example, a greater number thereof could be assembled within the same vacuous space. In this case the cold photo-electric cathodes of the first stages or multiple electrode systems each comprising an anode and a cathode could be excited in the same manner as described in connection with Figure 1 for the system comprising elements 5, 6, 8. 70 75 80

Figure 2 illustrates another sort of a combination composed of cold and incandescent cathodes. In this case, a straight filament 14 is employed which is enveloped by a grid 15 and a plate 16 diagrammatically indicated. The plate could likewise consist of wire gauze or netting. 14, 15, 16 is the power triode or multiple electrode system operated thermionically, and constituting the end stage or end triode system. There is further disposed inside the tube the cold cathode 17 which is covered up by an apertured grid 18, and a plate 19. The system 14, 16 delivers part of its electrons into the surrounding space. These are collected by the cathode 17 and cause the issuance of secondary electrons which are controlled by the grid 18 and are led off by plate 19. This action can be further assisted if, for example, the cathode 17 is united by way of a low-potential source 20 supplying a few volts to one end of the filament 14. The power to be amplified to a slight extent is fed to the grid 18. Between cathode 17 and the plate 19 is an accelerating plate potential which draws the secondary electrons, which are controlled by the grid 18, to the plate. The lead-in for the plate potential required by the first system can be effected at 21. At the same time, similarly as above described, control of grid 15 can be effected by the potentials amplified in the first triode or multiple electrode system 17, 18, 19. Also in this manner, cold and hot cathodes can be combined in such a manner that thermo-electric heating will be required only in the last-stage or last triode or multiple electrode system. 110 115 120

It is evident that the building of multiple-unit tubes is substantially simplified if only a single hot filament has to be provided, that is, for the last stage or system, and all preceding stages are excited by cold cathodes so that these cathodes require but one lead-in. 125

As shown in Figure 1, the electron supply lead need not be brought to the outside, indeed, it may be run inside the tube itself. Multiple-unit tubes do not exhibit any ap- 130

preciable larger consumption of heating and plate current than the last-stage system alone. For example, if the tube comprises three amplifier systems, two of which are being run with cold cathodes as hereinbefore described, and the last stage is operated thermo-electrically the saving realized in heating and plate current will be apparent. It is also clear that this is a radical and decided step forward in the art of building radio tubes.

It may be also mentioned that the arrangement according to Figure 2, although intended for the utilization of secondary electrons, represents an arrangement also suited for photo-electric operation. If desired, both the photo-electric action as well as the generation of secondary electrons may be combined. Indeed, this result will be readily obtained if the light produced by the filament 14 is allowed to act directly upon the surface of the cathode 17 and if in addition primary electrons originating from the filament 14, are allowed to directly impinge upon the cathode 17 with the result that secondary electrons are generated.

Having thus described my invention what I claim is:

1. A multi-stage amplifier tube housing an end triode system having an anode and a cathode adapted to emit electrons and light, and a preceding triode system having a cathode independent of said first cathode and anode and adapted to emit electrons by virtue of the luminous emission from the cathode of the end triode system.

2. An amplifier comprising a plurality of independent triode systems, one of the systems having a cathode adapted to emit electrons when heated, a cathode in another system independent of said first system adapted to emit electrons when exposed to light rays, said systems being enclosed by a single vessel.

3. An amplifier comprising a plurality of triode systems confined within a single vessel, light responsive means in one of the systems and means on the surface of the vessel to concentrate light on the light responsive means.

4. An evacuated amplifier tube housing an end stage and a preceding stage, each of said stages including an anode, control electrode, and a cathode, light responsive means on the cathode in the preceding stage, the anode, control electrode, and cathode in the preceding stage being independent of the anode, control electrode and cathode in the end stage.

5. In combination, a gas-tight container, a thermionic device disposed in said container and including an anode and cathode, the cathode being provided with a photoelectric coating, a second thermionic device disposed in said container and including an anode and a cathode, and means on the surface of the container to concentrate light from the

cathode of the second thermionic device on the photo-electric coating.

6. An electron discharge device comprising a gas-tight vessel, a thermionic device disposed within said vessel and including a cathode, a discharge-controlling element surrounding said cathode, and an anode surrounding said element, a second thermionic device disposed in said vessel including a cathode and anode, the cathode of the second thermionic device being provided with means whereby it emits electrons by photo-electric action when the cathode in the first thermionic device emits electrons.

7. A multi-stage amplifier tube housing an end triode system having a thermionic cathode, and a preceding triode system having a photo-electric cathode.

8. A multi-stage amplifier tube housing an end multiple electrode system including an anode and cathode wherein electrons are emitted from said cathode, a preceding multiple electrode system including a cathode independent of said first cathode and anode, and means on said second cathode whereby the electron emission of said preceding system is caused photo-electrically by light from said end stage.

9. In combination, a tube, a plurality of independent triode systems disposed in said tube, each system including a cathode, and means whereby the electron emission from one of the cathodes is caused by light emitted from the other cathode.

10. In combination, an amplifier tube comprising, a plurality of multiple electrode systems, one of said systems being an end stage and having a heatable cathode, and another of said systems being a preceding stage and having a cold cathode, the latter being provided with light responsive coating whereby emissions from the heated cathode cause electron emission from the cold cathode.
